UNITED STATES PATENT OFFICE.

JOHN T. H. PAUL, OF CHICAGO, ILLINOIS, ASSIGNOR TO E. GOLDMAN & COMPANY, INC.,
OF CHICAGO, ILLINOIS, A CORPORATION OF ILLINOIS.

CENTRIFUGAL PUMP.

1,012,271.

Specification of Letters Patent. Patented Dec. 19, 1911.

Application filed April 20, 1911. Serial No. 622,202.

To all whom it may concern:

Be it known that I, JOHN T. H. PAUL, a citizen of the United States, residing at Chicago, in the county of Cook and State of Illinois, have invented a new and useful Improvement in Centrifugal Pumps, of which the following is a specification.

The object of my invention is to provide an improved construction of centrifugal pump to the ends of facilitating its manufacture and increasing its efficiency.

In the accompanying drawings, Figure 1 shows my improved pump by a view in front elevation; Fig. 2 is a view in sectional end-elevation on line 2, Fig. 1; Fig. 3 is a plan view of the pump; Fig. 4 is a section on line 4, Fig. 3; Fig. 5 is a plan view showing the united three sections in which the lower part of the pump is formed; Fig. 6 is a similar view of the three sections of the upper portion of the pump in unassembled relation; Fig. 7 shows, by a view in elevation, the driven shaft of the pump with the two hollow vane-equipped heads thereon; Fig. 8 is an enlarged section on line 8, Fig. 1 or Fig. 4, and Fig. 9 is a view in side elevation of one of the two similar pump-heads, showing the in-take opening in one side of the shell.

The pump-shaft 10 carries a belt-pulley 10¹, or motor, on one end and between its ends, to render my improved device a two-phase pump, a pair of similar hollow heads 11 and 12 of wheel-like form and of the peculiar construction which is most clearly illustrated in Figs. 7, 8 and 9. The head is preferably a casting of brass. It has a relatively-large annular intake-opening 14 in its outer side concentric with its axis and surrounded by an external annular flange 13, and the sides converge slightly, both externally and internally, adjacent to the periphery, which contains six outlet-openings or ports 15 equidistant apart. The side opposite that containing the opening 14 is provided with an external annular flange 16, like the flange 13, and a central elongated bearing 17, at which it is keyed to the shaft 10, this bearing being continued partway through the chamber of the head as the center of the inner face of the respective side thereof, the cross-section of which approximates the arc of a circle, as shown in Fig. 4. Vanes 18, of which three are shown equidistant apart, join the inner

faces of the sides and extend from points near the bearing 17, each of these vanes curving throughout its length past an outlet-opening 15 and terminating in the advance-end of the latter. Three other vanes 19 alternate with the vanes 18 and are like them in all respects except that they are shorter, their inner ends registering with the inner edge of the collar or flange 13; and each vane 19 also terminates in the advance-end of an outlet-opening 15. The purpose of the described construction of the head is to present only rounded surfaces to the liquid in coursing through it, thereby to reduce friction to the minimum and avoid the presentation of obstructions or impediments to its flow.

The pump-casing is formed of lower and upper sections and each of these sections is composed of three sub-sections. Of these latter, the two outer sub-sections of the lower half of the casing are castings, each comprising a web-reinforced outwardly-extending and laterally tapering shelf-portion 20 having bolted to it the lower part of a capped and babbitted shaft-bearing 21 and provided with a leg 22 terminating in a foot 23 through which to bolt it down upon a suitable supporting bed or base, which is indicated by a line at 24 in Figs. 1, 4 and 8. The casing contains two similar annular central chambers 25 and 26, side by side, and two end-chambers 27 and 28, with an inlet-pipe 29 opening into the bottom of the chamber 27, an outlet-pipe 30 leading from the bottom of the chamber 26, both pipes extending on one side of the casing, and a pipe 31 crossing the pipe 30 and connecting the bottom of the chamber 27 with that of the chamber 28.

To produce the described casing-structure, end-portions 32 and 33 of its lower section are cast with the respective shelf-portions 20, and one (that at the left-hand end) includes in the casting a section of the pipe 31. The central portion 34 of the lower casing-section is a semi-circular casting formed with the halves of the annular chambers 25 and 26 in its walls, which chambers increase in diameter toward their discharge-openings, as represented of the chamber 25 in Fig. 8; and this casting is suitably flanged externally to inter-fit with corresponding flanges on the end sub-sections, through which to bolt the parts to

gether, the part 34 containing a central shaft-bearing 35 and being provided with semi-circular inner collars 36, 36 to fit about the head-flanges. Similar half-collars 37 are provided on the inner faces of the sub-sections 32 and 33 to fit about the head-flanges 13. The other section of the connecting-pipe 31 is also part of the casting 34, both pipe-sections being suitably flanged, whereby when the sub-sections of the lower section of the casing are adjusted together and fastened by bolts, these pipe-sections will meet and may be bolted together through their flanges. The sub-sections 32¹, 33¹ and 34¹ (Fig. 6) of the upper section of the casing are substantially counterparts, respectively, of the sub-sections 32, 33 and 34, except that they are devoid of inlet, outlet and connecting pipes; and they fit accurately upon the respective lower sub-sections, and are, like them, suitably flanged externally to adapt them to be bolted together and to the lower sub-sections whereby they complete the chambers 25, 26, 27 and 28, and the collars 36. With the sub-sections of the lower part of the casing assembled (Fig. 5), the shaft 10, carrying the heads 11 and 12, is adjusted at its end-portions in the bearings 21, 35, and outwardly-flaring sleeve 38, 38 upon it, fit at their inner ends against the opposing ends of the head-bearings 17, the expanded ends of the sleeves fitting against the inner end-walls of the sub-sections 32 and 33, whereby these sleeves form continuations of the cross-sectional arcs described, respectively, by the chamber 27 and chamber in the adjacent head 11, and by the chamber 26 and that in the adjacent head 12. When the shaft is placed in position, the casing-sections 32¹, 33¹ and 34¹ are adjusted in place and bolted together and to the lower section. As will be observed, each sub-section 32 and 33, and the corresponding sub-sections of the upper section of the casing, have formed in their outer sides interfitting sections of stuffing-box members 39 about bearings for the shaft, which is provided with collars 40, 40 to embrace the glands at their inner ends and stay the shaft against longitudinal displacement; and these glands form parts of the stuffing-boxes illustrated. With the parts of the pump assembled, it is ready to be operated as follows:—The shaft being in motion, the liquid to be pumped, as water, entering the device by way of the inlet 29, discharges into the chamber 27, whence it enters the rotating head 11 through its opening 14 and is thrown centrifugally into the casing-chamber 25 through the head-ports 15, under the direction of the vanes 18 and 19. From the chamber 25 the water discharges by way of the connecting-pipe 31 into the chamber 28, whence it enters the head 12 at its opening

14 and is thrown, under the guidance of the vanes in that head, through the ports 15 thereof into the chamber 26, whence it discharges at the outlet 30.

By the described sectional construction of the casing, the manufacture is greatly facilitated and the opposing surfaces of the sections may be conveniently tooled, without laborious and expensive work, to render them accurately interfitting, thereby saving leaky-joints requiring packing and frequent repairs; and the course of the liquid through the casing is so curved throughout as to present the least friction to it and to avoid other impediment tending to impair desirable uniformity to its flow.

The construction of each head 11 and 12 also facilitates and causes uniformity in the flow of the liquid through them, since the curved courses through the head-ports produced by the vanes reduce friction to the minimum besides avoiding impediment to the flow, while the relatively-shorter length of the vanes 19 prevents excessive churning action on the liquid. Moreover, as will be seen, the successive vanes so lap each other, toward their outer ends, as to overcome all tendency to radial back-lash of the liquid from the periphery toward the center of the head, by interposing the vanes as obstructions to radial back-pressure of the liquid from the casing-chambers into the heads.

What I claim as new and desire to secure by Letters Patent, is—

1. In a centrifugal pump, the combination with a shaft, of a casing having its lower part formed of laterally interfitting flanged sections and its upper part formed of similar sections accurately seating upon and bolted to the lower sections, the end-sections forming end-chambers with an inlet leading to one of said chambers, and the intermediate sections forming a pair of annular chambers, one of said annular chambers having a pipe-connection with the other end-chamber and the other annular chamber having an outlet, and a pair of wheel-like heads on the shaft, one in each of said annular chambers and each provided with an inlet in its outer side opening to an end-chamber, a circumferential series of peripheral ports, and a circumferential series of curved vanes each leading to a different port.

2. In a centrifugal pump, the combination with a shaft, of a casing having its lower part formed of laterally-interfitting flanged sections and its upper part formed of similar sections accurately seating upon and bolted to the lower sections, the end-sections forming end-chambers with an inlet leading to the bottom of one of said chambers, and the intermediate sections forming a pair of annular chambers, one of said end-cham-

bers and one of said annular chambers each having a curved pipe-section extending from its base, said pipe-sections being connected at their meeting-ends and forming 5 with said connected chambers a curved course through them, the other annular chamber having an outlet leading from its base, and a pair of vane-containing hollow heads on the shaft in the annular chambers 10 and provided with circumferential series of peripheral ports to each of which a different vane leads.

3. In a centrifugal pump, the combination with a shaft, of a casing having its 15 lower part formed of laterally-interfiting flanged sections and its upper part formed of similar sections accurately seating upon and bolted to the lower sections, the end-sections forming end-chambers having annular internal collars and provided with an 20 inlet leading to one of said chambers, and the intermediate sections forming a pair of annular chambers provided with annular internal collars, one of said annular chambers having a pipe-connection with the other 25 end-chamber, and the other annular chamber having an outlet, and a pair of vane-equipped hollow port-containing heads on the shaft, one in each of said annular chambers and each provided with annular flanges 30 on its opposite sides surrounded by said collars and an inlet in its outer side opening to an end-chamber.

4. In a centrifugal pump, the combination with a shaft, of a casing formed of laterally interfiting end and intermediate sections, the end-sections forming end-chambers with an inlet leading to one of them, and the intermediate section forming a pair 40 of annular chambers, one of which has a

pipe-connection with the other end-chamber and the other annular chamber having an outlet, a pair of vane-containing hollow port-equipped heads on the shaft, one in each of said annular chambers and each 45 provided with an inlet in its outer side opening to an end-chamber and on its opposite side with a radially-curving inner face and an elongated central bearing about the shaft extending part way through the head, and 50 outwardly-flaring sleeves on the shaft in said end-chambers meeting the heads of said bearings.

5. In a centrifugal pump, the combination with a shaft, of a casing having its 55 lower part formed of two flanged end-sections each provided with a webbed shelf-portion and legs and a flanged central section, said sections interfiting laterally and being bolted together, and its upper part 60 formed of two flanged end-sections and a flanged central section interfiting laterally and bolted together, said upper part accurately seating upon and being bolted to said lower part, the end-sections forming 65 end-chambers with an inlet leading to one of said chambers, and the intermediate sections forming a pair of annular chambers having a pipe-connection with the other end-chamber, and the other annular chamber having an outlet, and a pair of vane-equipped port-containing hollow heads on the shaft, one in each of said annular chambers and provided in their outer sides with inlets opening to said end-chambers.
